UNITED STATES PATENT OFFICE.

WILLIAM M. MARLEAN, OF BELVIDERE, ILLINOIS, ASSIGNOR OF ONE-HALF TO WILLIS S. BROWN, OF BELVIDERE, ILLINOIS.

SPARK-PLUG.

1,139,694.

Specification of Letters Patent. Patented May 18, 1915.

Application filed September 29, 1911. Serial No. 651,945.

To all whom it may concern:

Be it known that I, WILLIAM M. MARLEAN, a citizen of the United States, residing at Belvidere, in the county of Boone and State 5 of Illinois, have invented certain new and useful Improvements in Spark-Plugs, of which the following is a specification.

This invention relates to sparking devices more particularly designated as spark plugs 10 and used in connection with combustion engines, and the principal object of the invention is to provide an improved, simple and cheap device of the class described, which shall be effective and efficient in operation.

Another object of the invention is to provide means whereby the sparking distance may be positively and readily adjusted, and the parts held firmly in their adjusted positions.

For the attainment of these ends and the accomplishment of other new and useful objects, this invention consists in the features of novelty in the construction, combination 25 and arrangement of the several parts generally shown in the drawing and described in the specification, but more particularly pointed out in the appended claims.

In the drawing, Figure 1 is a cross sectional view, in elevation of a spark plug constructed in accordance with the principles of my invention, and positioned in the wall of a combustion chamber. Fig. 2 is a view on the line 2—2 of Fig. 1. Fig. 3 is a detailed view of a packing ring.

Some difficulties are experienced in the sparking devices now used among which may be noted the tendency of the tip of one of the electrodes to bend or become pitted by 40 the action of the spark, and also the inability properly to adjust the spark gap between the electrodes. This invention has for its object to obviate these difficulties and provide means whereby the movable electrode 45 may be positively positioned with respect to the other electrode, to vary and adjust the spark gap.

Referring more particularly to the drawing, a casing 10 is provided at one end 11 with external threads to secure it in the wall of a combustion chamber and with this end partially closed but forming a central opening 12. The other end of the shell is preferably larger in size and is internally threaded 55 to receive the removable shell 13. The

shell 13 is formed at the outer end with an enlarged shoulder 14 which is adapted to abut the outer end of the casing 10 so that when the shell 13 is threaded or screwed into the casing it will always assume the same 60 relative position, hence it may be removed and replaced as often as desired without destroying the adjustment of the other parts related to it. The inner edge of the shell 13 is threaded preferably at the ends to receive 65 the adjusting members 15 and 16. The outer ends of these members 15 and 16 preferably project without the shell 13 and are provided with nut-shaped portions 17 and 18 to facilitate their adjustment in the shell. 70 The inner edges of the adjusting members are preferably provided with inclined faces 19 and 20.

Positioned within the shell 13 is an insulating sleeve 20 formed with an enlarged 75 portion 21 having the inclined faces 22 and 23, which are adapted to correspond with the inclined faces of the adjusting members. Interposed between the faces of the adjusting members and the sleeve 20, are gaskets 80 24. These gaskets may be of any well known form or construction, and a suitable gasket is made by placing fibrous material 25 between metal strips 26 as shown by Fig. 3.

Disposed within the sleeve 20, and fitting 85 tightly therein is an electrode 27. This electrode is preferably formed with a shoulder 28 which is adapted to be inserted in a preferably circular opening 29 at the inner end of the insulating member 20 and which bears 90 against a shoulder 30 formed therein. If desired, a gasket may be inserted between the shoulder 28 and the shoulder 30. The inner end of the electrode is formed with an enlargement or ball 31 at the end thereof, 95 the diameter of which is less than the diameter of the opening 12 in the casing 10. It will be seen that the tip and the lower portion of the electrode is of the same material as the rest of the electrode, and that it is 100 large in size to prevent pitting caused by the action of a spark between the electrodes and is also large in size, compared to tips composed of higher resistance metal so that there is no danger of the tip becoming bent 105 or displaced. The electrode is further secured in position within the insulation 20 by means of a lock-nut 32 positioned on the outer end 33 which is threaded to receive the lock-nut 32 and the nut 34 which is 110

adapted to bind an electrode connection 35 in position. Between the lock-nut and the insulating sleeve 20, there may be positioned a gasket 36 and a spring washer 37.

5 In adjusting the spark gap of this device, it is evident that it is necessary only to move the electrode 27 longitudinally in the casing. This is effected by means of the adjusting members 15 and 16 which are forced against 10 the shoulders of the enlarged portion 21 of the insulating sleeve to hold it positively in position. It will be evident that the lower member 15 may be positioned in the shell 13 before the shell is inserted in the casing 10 15 and the sparking distance adjusted or varied before the casing is placed in position. Then by screwing in the shell 13 until the shoulders 14 abut the outer end of the casing, the position of the ball 31 of the electrode 27 with respect to the opening, will be fixed, and as long as the adjusting member 15 remains in its adjusted position, the spark gap between the two electrodes adjacent to ball 31, will remain the same when the shell 25 13 is screwed down with the shoulder 14 abutting the end of the casing. The electrode and the insulating sleeve 20 are readily adjustable and removable, as it is necessary only to remove the upper adjusting member 30 16 to remove the electrode 27 and the insulating sleeve 20 from within the shell. It will furthermore be noted that the electrode 27 and the opening 12 are at all times in positive alinement. This will insure that 35 there is no difference in the length of the spark gap between the ball 31 and the edges of the opening 12 at any of the points. By making the portion of the electrode 27, between the shoulder 28 and the ball 31, large 40 in size, not only is the rigidity of the electrode insured but also an economy is effected in the cost of construction of the electrode, for by making it of the same material as the remainder of the electrode, the construction 45 is simpler and cheaper. It will also be noted that by means of the adjusting members 15 and 16, the position of the electrode and the insulating sleeve 20 may be adjusted in either direction. In many sparking devices there is an adjustment in one direction only, but in this device it is manifest that the adjustment may be in either direction. If desired, the ball 31 may be made removable 50 55 from the other part of the electrode 27, the object being to permit of the use of any non-corrosive or special metal; such, for example, as high-carbon steel.

What I claim is:

1. In a device of the class described, the 60 combination of an electrode, an insulating sleeve with an enlargement inclosing said electrode, a metallic shell threaded on the inside and surrounding the sleeve, adjustable means in the ends of the shell to secure 65 and position the sleeve in the shell, and

means adapted to be secured in the wall of a combustion chamber for supporting the shell and forming the second electrode for the device.

2. A sparking device comprising an electrode, an insulating sleeve with an outside enlargement and inclosing said electrode, a metal shell threaded on the inside and surrounding said sleeve, adjustable means for engaging the enlargement at both sides and for adjusting the position of the sleeve and the electrode with respect to the shell, and means to secure the shell to the wall of a combustion chamber and to form a second electrode. 70 75 80

3. A sparking device comprising an electrode, an insulating sleeve with an outside enlargement and inclosing said electrode, a metal shell threaded on the inside at both ends and surrounding the said enlargement, adjustable members threaded in the ends of the shell and engaging both sides of the enlargement to position the sleeve in the shell, and an outer metallic casing to receive the shell and to form the other electrode for the sparking device. 85 90 95

4. In a sparking device the combination with an outer casing having a central aperture therein at one end, of a threaded shell adapted to screw into and abut said casing, an electrode having a tip adapted to be positioned in proximity to the said aperture, an insulating sleeve inclosing the electrode, and means carried by said shell for engaging said sleeve and for adjusting it in said shell whereby the electrode may be positioned with respect to the casing which forms the second electrode. 100 105

5. In a device of the class described the combination with a casing adapted to be positioned in communication with a combustion chamber, formed with a central aperture at one end and threaded internally at the other end, of a shell externally and internally threaded and adapted to fit within the casing and having a shouldered end to abut the said casing, an electrode having a tip smaller than the said aperture, an insulating sleeve in which said electrode is mounted and having an enlarged portion adapted to be inserted in the shell, members threaded to fit inside the shell and to be moved against the enlarged portion on both sides to position the sleeve and the tip with respect to the aperture in the casing. 110 115 120

6. In a sparking device for combustion engines the combination with a casing threaded externally at one end and internally at the other, the first named end having a central opening therein, of a shell internally and externally threaded and adapted to abut said casing at the other end, threaded adjusting members with inclined faces disposed in the shell, an insulating sleeve with a correspondingly inclined en- 125 130

largement adapted to fit in the shell and between the two adjusting members, and an electrode disposed within the insulating sleeve having a tip at the inner end extending into the opening at the end of the casing, and the outer end of the electrode projecting from the insulating sleeve to provide means for electrical connection.

7. In a sparking device for combustion engines, the combination with a casing having an opening and adapted to be inserted in the wall of a combustion chamber and constituting one of the electrodes of the device, of a shell threaded therein, the shell being provided with an enlarged shoulder which abuts the outer end of the casing, another electrode with a tip smaller than the said opening and means for electrical connections at the other end, an insulating sleeve surrounding the electrode and having an enlarged portion with inclined faces at the ends, the enlarged portion being of a size to fit within said shell, adjustable members threaded in the shell having inclined faces corresponding with the faces of the enlarged portion of the insulating sleeve and adapted to position the said sleeve with respect to the shell, and packing gaskets interposed between the said corresponding faces and comprising a non-combustible fibrous material positioned between metal rings, the said casing sleeve and the top adjusting member being provided with nut-shaped tops whereby they may be engaged by a wrench.

8. In a sparking device, the combination with a casing adapted to be inserted in a combustion chamber and having a central circular opening at the bottom, a sleeve mounted in the casing and having an outer enlarged portion which forms a shoulder to engage the outer end of the casing, an electrode formed with a shoulder, and an enlarged spherical shaped portion at the extremity less in diameter than the diameter of the said central opening, an insulating sleeve surrounding the electrode and having an internal shoulder coöperating with the shoulder on said electrode, said insulating sleeve being adapted to position the electrode in alinement with the central opening and to vary the sparking distance therebetween by longitudinal adjustment of said insulating sleeve, and means to effect said longitudinal adjustment in either direction.

9. In a sparking device, the combination with an outer casing having an electrode therein at one end, of a threaded shell adapted to screw into and abut said casing, a second electrode having a tip adapted to be positioned in proximity to the said first electrode, an insulating sleeve inclosing the second electrode, and means carried by said shell for engaging said sleeve and for adjusting it in said shell whereby the second

electrode may be positioned with respect to the casing which forms the first electrode.

10. In a device of the class described, the combination with a casing adapted to be positioned in communication with a combustion chamber provided with an electrode at one end and threaded internally at the other end, of a shell externally and internally threaded and adapted to fit within the casing and having a shouldered end to abut the said casing, a second electrode having a tip, an insulating sleeve in which said second electrode is mounted and having an enlarged portion adapted to be inserted in the shell, members threaded to fit inside the shell and to be moved against the enlarged portion on both sides to position the sleeve and the tip with respect to the first electrode.

11. In a sparking device for combustion engines, the combination with a casing threaded externally at one end and internally at the other, the first named end having an electrode, of a shell internally and externally threaded and adapted to abut said casing at the other end, threaded adjusting members with inclined faces disposed in the shell, an insulating sleeve with a correspondingly inclined enlargement adapted to fit in the shell and between the two adjusting members, and a second electrode disposed within the insulating sleeve having a tip at the inner end extending into proximity to the first electrode at the end of the casing and the outer end of the second electrode projecting from the insulating sleeve to provide means for electrical connection.

12. In a sparking device for combustion engines, the combination with a casing adapted to be inserted in the wall of a combustion chamber and constituting one of the electrodes of the device, of a shell threaded therein, the shell being provided with an enlarged shoulder which abuts the outer end of the casing, another electrode with a tip at one end and means for electrical connections at the other end, an insulating sleeve surrounding the electrode and having an enlarged portion with inclined faces at the ends, the enlarged portion being of a size to fit within said shell, adjustable members threaded in the shell having inclined faces corresponding with the faces of the enlarged portion of the insulating sleeve and adapted to position the said sleeve with respect to the shell, and packing gaskets interposed between the said corresponding faces and comprising a non-combustible fibrous material positioned between metal rings, the said casing sleeve and the top adjusting member being provided with nut-shaped tops whereby they may be engaged with a wrench.

13. In a sparking device, the combination with a casing adapted to be inserted in a

- combustion chamber and having an electrode at the bottom, a sleeve mounted in the casing and having an outer enlarged portion which forms a shoulder to engage the outer 5 end of the casing, an electrode formed with a shoulder and a tip, an insulating sleeve surrounding the electrode and having an internal shoulder coöperating with the shoulder on said electrode, said insulating sleeve 10 being adapted to position the electrode in proximity to the first electrode, and to permit of its longitudinal adjustment by a longitudinal adjustment of said insulating means.
- 15 14. In a spark plug of the class described, a body shell adapted to be secured in the wall of a combustion chamber and threaded internally, comprising one electrode, a tubular shell adapted to be screwed into said 20 body portion, an insulator disposed within said tubular shell and having a beveled enlargement, glands adapted to be screwed

into said tubular shell from each end for clamping said insulator firmly in position, a rod or stem extending longitudinally 25 through said insulator and forming an electrode at its lower end in sparking relation to said other electrode, said insulator having an enlarged central opening forming a chamber surrounding said stem and terminating substantially centrally with respect to said enlargement to prevent said insulator from cracking, an enlargement on said stem positioned within said enlarged opening in said insulator and means yieldingly clamp- 30 35 ing said stem in position.

In testimony whereof I have signed my name to this specification, in the presence of two subscribing witnesses, on this 26th day of September A. D. 1911.

WILLIAM M. MAREAN.
